Primary Examiner — Leanne Was-Englehart(74) *Attorney, Agent, or Firm* — Craft Chu PLLC;
Andrew W. Chu(57) **CLAIM**

The ornamental design for a door panel frame, as shown and described.

DESCRIPTION

FIG. 1 is a front perspective view of the door panel frame showing my design, including hinge connectors in broken lines.

FIG. 2 is a front elevation view thereof, including hinge connectors in broken lines;

FIG. 3 is a back elevation view thereof, including hinge connectors in broken lines;

FIG. 4 is a side elevation view thereof, including hinge connectors in broken lines;

FIG. 5 is an opposite side elevation thereof;

FIG. 6 is a top plan view thereof;

FIG. 7 is a bottom plan view thereof; and,

FIG. 8 is an enlarged partial side perspective view thereof, showing a handle attachment in broken lines.

The drawings contain a symbolic break. The portion between the break lines forms no part of the claimed design.

The broken lines in FIGS. 1-4 indicate hinge connectors as environment and form no part of the claimed design.

The broken lines in FIG. 8 indicate a handle attachment as environment and form no part of the claimed design.
